UNITED STATES PATENT OFFICE.

CHARLES L. GOUGHNOUR, OF CANTON, OHIO, ASSIGNOR TO THE UNITED ELECTRIC COMPANY, OF CANTON, OHIO, A CORPORATION OF OHIO.

DESIGN FOR A VACUUM-CLEANER.

42,747.

Specification for Design.

Patented July 9, 1912.

Application filed April 15, 1912. Serial No. 691,042. Term of patent 14 years.

To all whom it may concern:

Be it known that I, CHARLES L. GOUGHNOUR, a citizen of the United States, residing at Canton, in the county of Stark and State of Ohio, have invented a new, original, and ornamental Design for Vacuum-Cleaners, of which the following is a specification, reference being had to the accompanying drawing, forming part hereof.

The figure is a perspective view of a vacuum cleaner, showing my new design.

I claim:

The ornamental design for a vacuum cleaner, as shown.

CHARLES L. GOUGHNOUR.
